UNITED STATES PATENT OFFICE

OTTO H. FRANK, OF BROOKLYN, NEW YORK

TOGGLE SWITCH

Application filed August 6, 1927. Serial No. 211,025.

My invention relates to toggle switches and admits of general use, but is of special value in toggle switches of the type usually operated by hand, and comprising a light and simple construction, easily standardized, and well adapted for quantity production.

More particularly stated, my invention comprehends a toggle switch in which is employed an improved mechanism for quickly making and breaking the electrical connections, and so arranged that, under tension of a spring, the contact blades of the switch are actuated at great speed.

My invention further contemplates various improvements in different parts of the toggle switch, for the purpose of improving the efficiency of the switch.

Reference is made to the accompanying drawing forming a part of this specification, and in which like reference characters indicate like parts throughout the several figures.

Figure 1 is a plan view of my improved switch, here shown as open, and with the gear case partly broken away.

Figure 2 is an end elevation of the switch.

Figure 3 is a side elevation of the same.

Figure 4 is a section on the line 4—4 of Figure 1, looking in the direction indicated by the arrows.

Figure 5 is a detail view, being a section through one of the mountings for the switch blades.

A base plate 6, which supports the various working parts, is made of insulating material.

Disposed centrally of the base plate 6, and extending upwardly therefrom is a gear case 7.

Located adjacent the four corners of the base plate are contact forks 8, 9, 10 and 11, carried respectively by foot plates 12, 13, 14 and 15.

Below each of these foot plates is an anchor plate 16, shown more particularly in Figure 3. The anchor plate is imbedded in the bottom of the base plate, and connected with the foot plate by means of screws 17, 18, as indicated in Figure 3.

A number of tongues 19, 20, 21, 22 project outwardly from the edges of the foot plate,

each tongue being carried by an anchor plate. These tongues are used for making connections with conductors, such as wires, cables or conducting cords, in the manner well known in this art, as for instance by soldering, brazing, clinching or the like.

The gear case 7, which is made of sheet metal, is provided with feet 23 integral to it, these feet being held upon the base plate by means of screws 24.

Two switch blades 25, 26, carried respectively by two heads 27, 28, are used for the purpose of engaging and disengaging the contact forks 8, 9, 10, 11.

The two heads 27, 28, are alike, only the head 28 will be described in detail, its construction being shown in Figure 5.

The head 28 carries a cap plate 29, for holding the switch blade 26 in position. A pair of screws 30, 30 extend through the cap plate 29 and switch blade 26, into the body portion of the head 28. A strip 31 of insulating material is interposed between the switch blade 26 and the adjacent portion of the head 28. Abutting this strip 31 are a pair of screws 34, which extend through the body portion of the head 28 and engage a supporting block 33, which is imbedded within the head 28.

The supporting block 33 is made of metal. There are two of these supporting blocks, in the respective heads 27, 28. Extending from the supporting blocks are two necks 35, 36, shown more particularly in Figures 1 and 2. These two necks being alike, the construction of each may be understood from Figure 5, showing the neck 36.

The neck 36 is provided with a hole 37, and extending into this hole is a shaft 38, carrying a gear wheel 39, as may be understood from Figures 4 and 5. A pin 40 holds the shaft 38 and the neck 36 firmly together. By this arrangement the switch blade 26 can be actuated by rocking movements of the gear wheel 39.

Journaled within the gear case 7 and therein located opposite the crank arm 41 is another crank arm 42, mounted upon a shaft 43 which extends through the wall of the gear case and carries the neck 35. A cross pin 44 extends from this crank arm 42 to the crank arm 41, so that the two crank arms 41 and 42

and the cross pin 44 together constitute practically a single crank. This crank, rocked back and forth as hereinafter described, communicates a rocking motion to the two heads 27 and 28, and thus to the two switch blades 5 25 and 26.

10 Journaled within the gear 7 and located near the bottom thereof is a shaft 46, shown more particularly in Figure 4. Mounted firmly upon this shaft is a gear wheel 45, the teeth of which mesh with the teeth of the gear wheel 39 above mentioned. The shaft 46 also carries a crank arm 47, similar to the crank arm 39 above described.

15 Another crank arm 48, journaled within the bottom of the gear case 7, is located opposite the crank arm 47. A cross pin 49 extends from the crank arm 47 to the crank arm 48, these parts together constituting essentially a single crank.

20 A tensile spring 50 extends from the cross pin 49 to the cross pin 44, so that the tension of this spring tends to draw these two cross pins toward each other and thus under certain conditions to actuate the cranks, as may be understood from Figures 3 and 4.

25 The gear case 7 is provided with a number of stop lugs 51, 52, 53, and 55, located to serve as limiting stops for the crank arms 41 30 and 47.

35 A toothed rack 55, having nearly but not quite the form of a gear wheel as indicated in Figure 4, is mounted upon a shaft 56, so that the teeth of the rack 55 mesh with the teeth of the gear wheel 39.

40 The rack 55 is provided with an arm 57, carrying a handle 58 of insulating material. The operator grasps the handle 58, and by swinging it in one of two directions of travel, closes or opens the switch.

45 In the drawing, Figure 2, the main movable parts of the switch are shown by full lines in the positions they occupy when the switch is open, and shown by broken lines in the position they occupy when the switch is closed.

50 Each time the handle 58 is shifted to the right or in a clockwise direction according to Figures 2 and 4, the switch blade 26 is rocked in a counter-clockwise direction according to these figures, and brought into engagement with the contact forks 10 and 11. At the same moment the switch blade 25 is rocked in the same direction of travel as the switch blade 55 26, and brought into engagement with the contact posts 8 and 9. Thus all contacts of the switch are simultaneously closed. By the reverse movement, namely, by shifting the handle 58 to the left according to Figures 2 60 and 4, the switch blades 25 and 26, shifted in a direction opposite to the one in which they moved before, are pulled out of engagement with the contact posts with which they are associated.

65 Referring more particularly to Figures

3 and 4, it will be noted that, under tension of the spring 50, the crank arms 41 and 47 are lodged against the stop lugs 51 and 52, and are held tightly thereagainst. If, now, the handle 58 is slowly rocked in a clockwise direction according to Figure 4 the rack 55, by turning in a clockwise direction, will cause the gear wheel 39 to turn clockwise and the gear 45 to turn counter-clockwise. This stretches the spring 50, and increases the tension thereof, until the crank arms become vertical, at which moment the spring 50 is at a maximum tension, and each of the crank arms is on center. The movement of the handle 58 being continued so as to move the cranks off center, the tension of the spring 50 becomes the initial power now closing the switch with a snap, the crank arms 42 and 48 being thus lodged against the stop lugs 54 and 53. Since both of these crank arms are in motion whenever the switch is being either opened or closed, and since the distances traveled by the two arms are virtually added, the throw of the switch may have considerable length in proportion to the relative sizes of the various parts, and the travel of the movable parts can be rendered very quick, positive, and reliable.

70 75 80 85 90 95 The action of my device may be readily understood from the foregoing description.

The parts being assembled and arranged as indicated in the drawing and as above described, the operator simply grasps the handle and swings it in the proper direction to open or close the switch.

100 Because of the quick and positive movements of the various movable parts, and because the throw of the switch blades may be extended a considerable distance in proportion to the relative sizes of the various parts, objectionable sparking is greatly reduced, or 105 prevented altogether.

110 Except as above otherwise indicated, the action of the switch is substantially like that of other snap switches heretofore known in this art.

I do not limit myself to the precise construction shown, as variations may be made therein without departing from my invention, the scope of which is commensurate with my claims.

115 Having thus described my invention, what I claim as new and desired to secure by Letters Patent is as follows:

120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930

cranks but connected therewith, for turning said cranks until said spring passes the dead centers of said cranks, and means for limiting the travel of said cranks.

5 2. The combination, with a plurality of stationary contact forks and a plurality of switch blades movable relatively to said contact forks for the purpose of engaging and disengaging the same, of a pair of cranks 10 geared to rock in opposite directions when actuated, a tensile spring extending from one of said cranks to the other, connections from said cranks to said switch blades for the purpose of actuating said switch blades, gearing 15 separate from said cranks but connected therewith, said gearing including a hand lever for actuating said gearing.

3. The combination, with stationary contact forks and switch blades movable relatively to said stationary contact forks for the purpose of engaging and disengaging the same, of a pair of cranks geared to rock in opposite directions when actuated, a tensile spring extending from one of said cranks to 20 the other, connection from said cranks to said switch blades for the purpose of enabling movements of said cranks to actuate said switch blades, and gearing separate from said cranks and connected therewith, for 25 actuating said cranks.

4. In an electric switch the combination of a plurality of stationary contact members, a plurality of switch blades movable relatively to said stationary contact members 35 for the purpose of engaging and disengaging the same, a pair of cranks geared to rock simultaneously in opposite directions when actuated, spring mechanism connected with said cranks for forcing said cranks toward each other after said cranks leave their dead centers, and gearing separate from said cranks but connected with said cranks for actuating the same, said gearing including a handle controllable by the operator for 40 shifting said cranks past their dead centers 45

5. In an electric switch the combination of a plurality of stationary contact members, a plurality of switch blades movable relatively to said stationary contact members for the 50 purpose of engaging and disengaging the same, a pair of cranks geared to rock simultaneously in opposite directions when actuated, spring mechanism connected with said cranks for forcing said cranks toward each other, said cranks and said spring being so 55 connected that said cranks arrive at their respective dead centers at the same time, so that said spring pulls said cranks toward each other as they leave their dead centers, and gearing separate from said cranks but connected with said cranks and controllable by the operator for shifting said cranks past 60 their respective dead centers, said gearing including a handle whereby it may be actuated.

Signed at New York city, in the county of New York and State of New York, this 5th day of August, 1927.

OTTO H. FRANK. 70
